UNITED STATES PATENT OFFICE.

LOUIS C. WALKER, OF MUSKEGON, MICHIGAN.

DESK.

1,072,280.

Specification of Letters Patent.

Patented Sept. 2, 1913.

Application filed February 28, 1912. Serial No. 690,442.

To all whom it may concern:

Be it known that I, LOUIS C. WALKER, a citizen of the United States, residing at Muskegon, in the county of Muskegon and 5 State of Michigan, have invented new and useful Improvements in Desks, of which the following is a specification.

The present invention relates to improvements in desks, and it comprehends, generally, a desk structure wherein the two cabinet sections consist each of a stack of so-called "individual units," these sections being connected by a top panel or top, which is detachably related thereto, so as to admit 15 of its being removed when it is desired to change the assemblage of units in either or both of the stacks, *i. e.*, to substitute units of a different type for any or all of these originally in a stack, or to add or withdraw units. 20 So far as this feature of the invention is concerned, the latter resides in certain improvements in the construction of the top panel or top, and of the top members of the cabinet sections.

25 The invention also, however, includes certain other improvements in or relating to said top panel, notably the provision of movable dummy side panels which are carried by the first-mentioned panel and are designed for coöperation with the bases on 30 which the stacks rest, to complete the sides of the desk and give the same a finished appearance, all of the improvements mentioned being hereinafter set forth and explained at 35 length.

A structural embodiment of the invention is illustrated in the accompanying drawings, wherein—

Figure 1 is a collective view of the parts 40 of the desk disassembled; Fig. 2 is a perspective view of the desk in a set-up condition, the view being taken from the rear of the desk; Fig. 3 is a front elevation, the top panel being shown in section; and Fig. 45 Fig. 4 is a transverse vertical sectional view, taken on the line 4—4 of Fig. 3.

In said drawings, 5 and 6 indicate in a general manner, the two cabinet sections of the desk, 7 the top panel, or top, and 8 the 50 rear panel, or back. Each of the cabinet sections consists primarily of a stack of individual units 9, which latter may be of various types and sizes and are removably assembled together and interlocked in the 55 manner shown and described in Patent No. 963,669, granted to Walker and Wilson and

dated July 5, 1910, to which reference may be had for an extended explanation. The stacks rest upon and are supported by suitable bases 10 that project a considerable 60 distance beyond the rear stack walls. The top members 11 of the stacks carry the usual sliding panels 12 and their side rails are connected by pairs of horizontal cleats 13, the members of each pair of cleats being spaced apart from each other and being 65 formed with central horizontal openings 14 arranged in alinement.

To the under face of the top panel 7, there is fastened a skeleton rectangular 70 frame comprising transversely arranged side rails 15 and 16 and longitudinal front and rear rails 17 and 18, said rails being located parallel with and adjacent to the corresponding edges of said panel. The 75 longitudinal rails are further connected by a centrally located pair of cross-rails 19 and 20 arranged parallel with the side rails. The rails 15 and 17 are each formed with pairs of seats 21 and 22 and projections or 80 lugs 23 and 24 which alternate with each other and are produced by cutting away portions of the rails, as shown in Fig. 1, the projections on one rail extending toward and being located directly opposite each 85 other. The location and proportions of these seats and projections are such that the projections 23 will fit squarely between the cleats 13 on top of section 5, while the seats will receive the adjacent ends of such cleats. 90 In like manner, the rails 16 and 20 are formed with alternating seats 25 and 26 and projections 27 and 28, said seats receiving the ends of the cleats 13 on the top of section 6, and said projections 27 fitting in the 95 spaces between said cleats. The projections 24 and 26 rest, in part, upon the rear portions of the top members 11 of the two sections and are thus supported. The arrangement is such, therefore, that the top panel 100 will rest squarely upon the tops of the two sections 5 and 6, and will be held firmly against movement from such position by the interlocking coöperation of the various cleats, projections and seats, as above described. To further preclude accidental displacement of the top panel, a pair of locking rods 29, one for each section, may be employed, if desired, these rods being inserted through openings 30 in the front 105 rail 17 of said panel, and through the openings 14 in cleats 13, the openings last men-

tioned alining with the rail openings 30, as will be understood.

To complete the sides of the desk and give the same a finished appearance, there is 5 hinged to the rear projection of each of the rails 15 and 16 a dummy panel 31. These panels are adapted to be swung downwardly into vertical position, so as to rest at their lower ends upon the bases 10, the latter being 10 provided with cleats 32 disposed transversely thereon and located rearwardly of the stacks. Said cleats interlock with panels 31 through the intermediary of transverse seats 33 formed in the panel ends, (see 15 Fig. 1).

Where the desk is designed to occupy a position in the center of a room, or any similar position where its back would be visible, the rear panel 8 will be necessarily employed, but this panel need not be used where the desk is disposed lengthwise against a wall or occupies any other position wherein its back would be concealed. Said panel, when used, is fitted between the top 20 panel and the bases 10, and rests at its lower longitudinal edge upon the latter, its inner face fitting flush against the rear edges of the dummy panels 31 and the cleats 32, (see Fig. 4). A locking device of any suitable 25 character, as, for instance, the strip 34, may be employed to hold panel 8 in place.

From the foregoing it will be seen that the top may be readily detached from the desk without changing the relative positions of 30 the two cabinet sections 5 and 6, whereupon the arrangement of the units comprising the stacks 9 may be varied to suit existing conditions. Moreover, by providing a top panel in connection with said stacks, the necessity 35 of utilizing a separate desk or table for writing purposes is obviated, since the structure as a whole is itself converted into a desk by the use of such panel. A considerable saving in space is likewise obtained 40 in this way, as will also be understood. Furthermore, the employment of the dummy panels renders the structure symmetrical by conforming it to the ordinary lines of desk construction.

50 I claim as my invention:

1. In a desk, the combination of a pair of cabinet sections each provided upon its top with a pair of horizontal transversely-arranged spaced cleats; and a top panel 55 movably mounted upon said sections and provided upon its under face, adjacent each side edge thereof, with a pair of rails arranged at right angles to the corresponding

pair of cleats, each pair of rails being provided with opposed seats wherein the ends 60 of the adjacent cleats are received, and with opposed projections fitting in the spaces between said cleats.

2. In a desk, the combination of a pair of spaced cabinet sections each provided upon 65 its top with a pair of spaced horizontal cleats; and a top panel mounted upon said sections and provided upon its under face with a pair of spaced horizontal rails for co-operation with each pair of cleats, each pair 70 of rails being formed with pairs of opposed seats wherein the ends of the corresponding cleats are designed to fit, and with a pair of opposed projections located intermediate said pairs of seats and designed to fit in the 75 spaces between said cleats.

3. In a desk, the combination of a pair of spaced cabinet sections each comprising a stack of individual units removably assembled together, and a base on which the same 80 is mounted, said bases projecting rearwardly beyond the corresponding stacks; a top panel resting upon said stacks and removably interlocked with the tops thereof; and a pair of depending dummy panels secured 85 to the opposite side edges of said top panel and arranged to rest at their lower edges upon the adjacent projecting portions of the corresponding bases, said dummy panels occupying the same plane as the outer side 90 members of the adjacent stacks.

4. In a desk, the combination of a pair of spaced cabinet sections each comprising a stack of individual units, and a base on which the same is mounted, said bases projecting rearwardly beyond the corresponding stacks and being each provided with a cleat; a top panel resting upon said stacks and removably interlocked with the tops 100 thereof; and a pair of depending dummy panels secured to the opposite side edges of said top panel and arranged to rest at their lower edges upon the adjacent projecting portions of the corresponding bases, said dummy panels occupying the same plane as 105 the outer side members of the adjacent stacks and having their said lower edges recessed for engagement with the corresponding cleats.

In testimony whereof I have hereunto set 110 my hand in presence of two subscribing witnesses.

LOUIS C. WALKER.
